TABLE LAMP OR THE LIKE

Robert James Cooke, 50—27 213th St., Bayside, N.Y.

Filed July 22, 1963, Ser. No. 75,902

Term of patent 14 years

(Cl. D48—20)

FIG. 1 is a front elevational view of a table lamp or the like embodying my new design;

FIG. 2 is a side elevational view thereof;

FIG. 3 is a side elevational view illustrating the opposite side from the side shown in FIG. 2;

FIG. 4 is a rear elevational view thereof;

FIG. 5 is a bottom plan view thereof; and

FIG. 6 is a top plan view thereof.

The dominant features of my design reside in the portions shown in full lines.

I claim:

The ornamental design for a table lamp or the like, as shown and described.
